PIPE TONGS

Chester Leon Coshow, Maracaibo, Venezuela

Application July 31, 1946, Serial No. 687,397

3 Claims. (Cl. 81—53)

1

This invention relates to improvements in rotary drill pipe tongs that are especially adapted to break tool joints or casing, while being run or pulled on a drilling or producing well.

The principal object of the invention is to provide a device of this character that is positive in action, simple and highly efficient in accuracy and construction, unique in operation, strong, durable, reliable and efficient in use and can not easily get out of order.

Another object of the invention is to provide a device which may be easily used to make up and run drill pipe and casing by eliminating all ropes and chains that are conventionally used in spinning drill pipe, thereby providing a device that is high in safety factors, since the extremely hazardous procedure of handling the rope or chain by a workman is eliminated as well as the necessity of having extra tong heads to change from one size of pipe to another.

With the above and other objects in view, the invention consists of the novel details of construction, arrangement and combination of parts more fully hereinafter described, claimed and illustrated in the accompanying drawings in which:

Figure 1 is an elevational view of an embodiment of the invention;

Figure 2 is a side view thereof;

Figure 3 is an end view thereof;

Figure 4 is a sectional view on the line 4—4 of Figure 3;

Figure 5 is a sectional view on the line 5—5 of Figure 2;

Figure 6 is a sectional view on the line 6—6 of Figure 3; and

Figure 7 is a perspective view of the removable shoe member.

Referring more in detail to the drawings, the reference numeral 10 designates the pipe tongs which comprise the elongated handle member 12 having the arcuate shaped pipe section gripping shoe member 14 detachably attached to the end of the handle member by means of bolts 16. A tongue 18 on the shoe member 14 properly seats the shoe member on the handle member and the gripping face of the shoe member 14 is serrated or roughened as at 19.

Along the medial line of the handle member 12 adjacent the end thereof on which the shoe member 14 is detachably connected are the pivot pins 22 which are in spaced parallel relation with each other and on which are pivotally and slidably mounted the tong jaw members 24 and 26 respectively, by means of their bifurcated ends 28, and the pins 22 are mounted in elongated

2

slots 29 in the handle member. The end of the handle member 12 extends beyond the pivot pins 22 so that the shoe member 14 is positioned between the jaw members 24 and 26.

5 The free ends of the jaw members meet in alignment at 30, and adjacent their meeting point, jaw member 26 is provided with an upstanding apertured ear 32 to pivotally mount the bifurcated end 34 of the latch dog 36 which is apertured to engage the lip 38 formed on the end of the jaw member 24.

On the inner face of the jaw members in opposed relation to the shoe member 14 in seats provided therefor, are mounted rollers 40 by means of pins 42 and these rollers and shoe member 14 are adapted to engage the casing 44 as shown in Figure 1.

Rotatably mounted on an axle 45 supported by the handle member 12 laterally of a side face 20 thereof near the shoe supporting end thereof and intermediate the pins 22 and shoe member 14 in a roughened surface drum 50 having rigidly secured to its outer surface by means of bolts 48, the spool 46. The drum 50 houses the spring 52 which is connected to the axle 45 and the inner surface of the drum 50 at 51 and 51', and causes the rewinding of the cable 54 on the spool after the operation of the tongs. The drum is provided with a roughened surface 56 which is adapted to engage a joint on the casing 44. The spool is provided with roller bearings 58 for the free rotation thereof on the axle 45 which is mounted in the bore 60 in the handle member 12 and fixed in the forked end 62 of the angular lever arm 64 by pins 66 and the lever arm 64 follows the conformation of the jaw member 24 and is provided on the forward end thereof with an eye 68 which engages the jaw member 24 adjacent its meeting point with the jaw member 26, the lever 64 being pivotally mounted on the jaw 24 at a location intermediate the ends of the lever arm and the jaw member 24 by means of the pivot pin 70.

45 The upper end of the handle member is provided with an arcuate shaped recess 72 which receives one end of the cable 74 which is connected to the cat head for tonging the pipe tight, and the cable 54 is connected to the cable 74 in 50 proper relation, as at 76. The recess 72 is closed by a plate 78 mounted thereover, which is secured to the handle member 12 by bolts 80, and an eye or staple 82 adjacent the recess is provided for connection to a spring not shown that 55 will pull the tong back in position for another stroke.

During operation of the tong, when lever 64 is moved on its pivot by means of a manual pull on the eye 68 by a rope or other means the lever 64 moves the roughened surface 56 of the drum 50 into engagement with the tool joint on the drill pipe or casing, forcing the latter to come into contact with the rollers 40 on the jaw members 24 and 26. Then by pulling the cable 54 which causes the spool 46 to rotate, the drill pipe or casing is forced into a snug position against rollers 40, such movement being accomplished by means of the pins 22 mounted in the elongated slots 23. Then when the pull on the lever is removed the housing 50 will move out of engagement with the drill pipe or casing so that when pressure is released on the cable, the spring 52 winds the cable back on the spool ready for another stroke when the lever 64 has again been moved on its pivot to return the housing into engagement with the drill pipe or casing. When engagement of the surface 56 with the drill pipe or casing will no longer rotate the drill pipe or casing the jaws may be latched in closed position, whereby the shoe member 14 grips the tool joint and then sufficient pressure is exerted on the handle to make a perfect joint. Cable 54 may be pulled as many times as necessary to force the pipe or casing into a snug position against rollers 40 for tonging, thereby making a speedier, faster and safer working drill pipe and casing tong. The drum 50 may be removed for resharpening of its surface 56, and the shoe member 14 is removable for replacement of various size shoe members according to the pipe being tonged.

It is believed that the operation and construction of the invention will be apparent to those skilled in the art, and it is to be understood that while the description and use of the invention has only been described as being used for the purpose of making and breaking a drill pipe and casing, it can be applied to making and breaking of any kind of pipe being run in or out of a drilling or producing well or on pipe being laid horizontally on the ground.

Having thus described the invention what is

claimed as new and desired to be secured by Letters Patent is:

1. A pipe tong comprising an elongated handle member, a pair of jaw members independently, pivotally and slidably mounted on the handle member, near one end thereof, pipe section gripping means including a roughened shoe detachably attached to an end of the handle member, between the jaw members, and a pair of rollers mounted one on each jaw member, and pipe joint gripping means including a roughened surface drum mounted laterally of a side face of the handle member on an axle supported by the handle member near the shoe-supporting end thereof, means for moving the drum into or out of engagement with the pipe joint, means for rotating the drum, and means for latching the jaw members in closed position about the pipe section.
2. The pipe tongs of claim 1, wherein the slideable connection for each jaw member to the handle member includes an elongated slot in the pivoted end thereof, through which its pivot pin extends; wherein the drum moving means includes an angular lever arm pivoted on one of the jaw members at a location intermediate the ends of the lever and the ends of the jaw member, and wherein the means for rotating the drum includes a tensioned coil spring within the drum, whose ends are secured to the drum axle and inner surface of the drum, respectively.
3. The pipe tongs of claim 2, wherein the coil spring within the drum is tensioned by pull on a rope wound on a spool which is supported on the drum axle and rigidly secured to the drum.

CHESTER LEON COSHOW.
